US0D1102701S

(12) **United States Design Patent** (10) **Patent No.:** **US D1,102,701 S**
(45) **Date of Patent:** **** Nov. 18, 2025**

(54) **SAFE**

(71) Applicant: **Weifeng Hu**, Jinhua (CN)

(72) Inventor: **Weifeng Hu**, Jinhua (CN)

(**) Term: **15 Years**

(21) Appl. No.: **29/955,873**

(22) Filed: **Aug. 5, 2024**

(51) LOC (15) Cl. **99-00**

(52) U.S. Cl.

USPC **D99/28**

(58) **Field of Classification Search**

(57) **CLAIM**

The ornamental design for a safe, as shown and described.

DESCRIPTION

FIG. 1 is a front, right and top perspective view of a safe, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged portion view taken from encircled portion, "9," in FIG. 1.

The even broken lines shown in the drawings illustrate portions of the safe that form no part of the claimed design. The dot-dash broken lines depict the boundaries of the enlarged portion view of FIG. 9 shown in FIGS. 1 and 9 and form no part of the claimed design.

1 Claim, 9 Drawing Sheets
